2,4,5 - TRILOWERALKYL - PYRROL - 3 - YL - HYDROXYMETHYL KETONES AND ETHERS AND CARBAMATES THEREOF

Irwin J. Pachter, Woodbury, and Karl Schoen, Kew Gardens, N.Y., assignors to Endo Laboratories, Inc., Garden City, N.Y., a corporation of New York
No Drawing. Filed Apr. 23, 1965, Ser. No. 450,520
5 Claims. (Cl. 260—326.3)

This invention relates to novel chemical compounds having valuable pharmacodynamic activity and therapeutic compositions embodying those compounds. More particularly, this invention relates to derivatives of hydroxymethyl pyrrol-3-yl ketone having muscle relaxing and tranquilizing properties, and to the preparation of such derivatives and formulations thereof as therapeutically useful compositions.

The therapeutically active compounds of this invention are represented by the following structural formula:

wherein:

the lower alkyl groups in positions 2, 4 and 5 have a maximum of six carbon atoms; and

R is hydrogen, a lower alkyl group of not more than six carbon atoms, carbamyl, a mono- or dihydroxy lower alkyl group of not more than four carbon atoms, a mono- or di-carbamyl lower alkyl group of not more than four carbon atoms, phenyl and nuclear-substituted phenyl, benzyl or phenethyl.

Most of the compounds of this invention are prepared through the action of alkali metal alkoxides, hydroxides or phenoxides on 2, 4, 5 lower alkyl chloromethyl pyrrol-3-yl ketones. The chloromethyl ketones result either from reaction of appropriate pyrroles with chloroacetonitrile and hydrogen chloride, followed by hydrolysis of the intermediate imino compounds, or through reaction of chloroacetyl chloride with Grignard derivatives of appropriate pyrroles.

Alternatively, the products of this invention may be prepared more directly through reaction of alkoxy- or phenoxy-acetyl chlorides with Grignard derivatives of appropriate pyrroles.

A third method consists in reacting the alkoxy- or phenoxyacetyl chlorides with the appropriate pyrrole and anhydrous aluminum chloride in a Friedel-Crafts reaction.

The useful carbamyl compounds are derived from the corresponding alcohols through standard procedures. One preferred method involves reacting the alcohol with an alkali metal cyanate under acidic conditions.

The compounds of this invention possess muscle relaxing properties and mild tranquilizing effects on the central nervous system. They are effective as skeletal relaxants and are useful in the management of anxiety and tension states with a minimal incidence of undesirable side effects.

They are active when administered to animals and humans orally, parenterally or rectally. The oral route is

2

preferred. Although they may be administered as pure compounds, their limited solubility in water makes it advantageous to combine them with pharmaceutical carriers such as starch, sugar, talc and the like to form powders which can be used directly or inserted into gelatin capsules or converted into tablets. Suitable lubricants like magnesium stearate, binders such as gelatin and disintegrating agents like sodium carbonate in combination with citric acid can be used to form tablets.

Unit dosage forms should generally contain a concentration of 1.0% to 50% by weight of one of the active compounds provided by this invention. In general, such unit dosage forms can contain about 10 to 400 mg. of active substance.

The following are examples in accordance with the invention. The temperatures are centigrade.

EXAMPLE 1

Hydroxymethyl 2,4,5-trimethylpyrrol-3-yl ketone

2,3,5-trimethylpyrrole was converted into chloromethyl 2,4,5-trimethylpyrrol-3-yl ketone by the method of Fischer, Schneller and Zerweck, Ber., 55, 2399 (1922).

To 20 g. of potassium hydroxide in 300 ml. of water was added 16 g. of chloromethyl 2,4,5-trimethylpyrrol-3-yl ketone and the mixture was heated under reflux for two hours, cooled and filtered. The solid product, upon recrystallization from methanol, melted at 188°.

EXAMPLE 2

Methoxymethyl 2,4,5-trimethylpyrrol-3-yl ketone

To a solution of 5 g. of sodium in 250 ml. of methanol was added 50 g. of chloromethyl 2,4,5-trimethylpyrrol-3-yl ketone. After six hours of heating under reflux, sodium chloride was filtered out and methanol was removed under reduced pressure. The residue was diluted with water and the product was collected and recrystallized from methanol. Yield 38 g., M.P. 138°.

EXAMPLE 3

Ethoxymethyl 2,4,5-trimethylpyrrol-3-yl ketone

This product was prepared by the method of Example 2 using ethanol in place of methanol, M.P. 111°.

EXAMPLE 4

Isopropoxymethyl 2,4,5-trimethylpyrrol-3-yl ketone

This product was prepared by the method of Example 2 using isopropanol in place of methanol, M.P. 100°.

EXAMPLE 5

Methoxymethyl 2,4-dimethyl-5-propylpyrrol-3-yl ketone

A Grignard solution was prepared from 7.3 g. magnesium filings and 33 g. ethyl bromide in 600 ml. anhydrous ether. To this solution 21 g. 2,4-dimethyl-5-propylpyrrole was added dropwise with stirring. Stirring was continued for two hours and the mixture allowed to stand overnight at room temperature. Methoxacetyl chloride 22 g. was then added dropwise with stirring and cooling. After stirring three hours the mixture was decomposed with 150 ml. of 15% ammonium chloride solution. The ether solution was separated, washed with aqueous sodium bicarbonate solution, then with water and dried over MgSO₄. The solvent was removed and the residue crystallized repeatedly from heptane; M.P. 120-124°.

3
EXAMPLE 6

Ethoxymethyl 2,4-dimethyl-5-propylpyrrol-3-yl ketone

This product was prepared by the method of Example 5 from 2,4-dimethyl-5-propylpyrrole and ethoxyacetyl chloride. Crystallized from heptane; M.P. 111-113°.

EXAMPLE 7

Methoxymethyl 2,5-dimethyl-4-propylpyrrol-3-yl ketone

This product was prepared by the method of Example 5 from 2,5-dimethyl-4-propylpyrrole (b. 13 mm 90-93°; n_D^{25} 1.4982) and methoxyacetyl chloride. Crystallized from heptane; M.P. 132-134°.

EXAMPLE 8

Ethoxymethyl 2,5-dimethyl-4-propylpyrrol-3-yl ketone

This product was prepared by the method of Example 5 from 2,5-dimethyl-4-propylpyrrole and ethoxyacetyl chloride. Crystallized from aqueous ethanol and heptane; M.P. 103-105°.

EXAMPLE 9

2-hydroxyethoxymethyl 2,4,5-trimethylpyrrol-3-yl ketone

This product was obtained by the method of Example 2 through use of ethylene glycol in place of methanol and heating on a steam bath rather than under reflux; M.P. 130°.

In similar fashion, the use of glycerol in place of ethylene glycol results in the synthesis of 2,3-dihydroxyethoxymethyl 2,4,5-trimethylpyrrol-3-yl ketone.

EXAMPLE 10

Carbamyloxymethyl 2,4,5-trimethylpyrrol-3-yl ketone

To 17 g. of hydroxymethyl 2,4,5-trimethylpyrrol-3-yl ketone and 13 g. of sodium cyanate in 100 ml. of methylene chloride was added, with stirring, 15.5 ml. of trifluoroacetic acid. The mixture was then stirred for eight hours and diluted with water. The organic layer was removed and the resulting product was recrystallized from methanol.

In similar fashion, the use of 2-hydroxyethoxymethyl 2,4,5-trimethylpyrrol-3-yl ketone in place of hydroxymethyl 2,4,5-trimethylpyrrol-3-yl ketone results in the formation of 2-carbamyloxethoxymethyl 2,4,5-trimethylpyrrol-3-yl ketone.

EXAMPLE 11

Phenoxyethyl 2,4,5-trimethylpyrrol-3-yl ketone

9 g. of chloromethyl 2,4,5-trimethylpyrrol-3-yl ketone in ethanol was added to an ethanolic solution of 7 g. of phenol and 4 g. of potassium hydroxide in ethanol. The resulting solution was heated under reflux four hours, concentrated and diluted with water. The solid product was recrystallized from ethanol; M.P. 132°.

EXAMPLE 12

2-methoxyphenoxyethyl 2,4,5-trimethylpyrrol-3-yl ketone

By the procedure of Example 10, using guaiacol in place of phenol, this 2-methoxy product was obtained; and purified by recrystallization from methanol; M.P. 128°.

EXAMPLE 13

4-butyl-2,5-dimethylpyrrol-3-yl methoxymethyl ketone

This product was prepared by the method of Example 5 from 4-butyl-2,5-dimethylpyrrole and methoxyacetyl chloride. It was purified by crystallization from heptane; M.P. 114-116°.

4
EXAMPLE 14

Ingredient:	Mg./tablet
Methoxymethyl 2,4-dimethyl-5-propylpyrrol-3-yl ketone	20
Lactose USP (spray dried)	170
Starch USP	10
Magnesium stearate USP	1
Stearic and USP	5
Flavor	Q.s.

All above ingredients were passed through a 60-mesh sieve, blended for 30 minutes and compressed directly into tablets on a suitable tablet press at a weight of 206 mg., using a $1\frac{1}{32}$ " biconcave scored punch.

EXAMPLE 15

Ingredient:	Mg./tablet
Hydroxymethyl 2,4,5-trimethylpyrrol-3-yl ketone	250
Lactose USP (impalpable)	60
Starch USP	140
Magnesium stearate USP	3
Stearic acid USP	10
Flavor	Q.s.

These tablets were granulated with starch paste in conventional fashion. They were dried, passed through a No. 20 mesh sieve and compressed on a suitable tablet press, using a $1\frac{1}{32}$ " biconcave punch at a weight of 463 mg.

EXAMPLE 16

Ingredient:	Mg./tablet
Carbamyloxymethyl 2,4,5-trimethylpyrrol-3-yl ketone	25
Lactose USP (spray-dried)	100
Magnesium stearate	1
Cab-O-Sil (amorphous silicon dioxide)	5

These ingredients were combined, blended and passed through a No. 1 screen of a Fitzpatrick comminutor machine before encapsulating into a two-piece hard gelatin No. 3 capsule on a standard capsulating machine at a net weight of 131 mg.

EXAMPLE 17

Ingredient:	Mg./tablet
Methoxymethyl 2,4,5-trimethylpyrrol-3-yl ketone	250
Lactose USP (spray-dried)	200
Magnesium stearate	1
Cab-O-Sil (amorphous silicon dioxide)	5

These ingredients were combined, blended and passed through a No. 1 screen of a Fitzpatrick comminutor machine before encapsulating with two-piece hard gelatin No. 0 capsules on a standard capsulating machine at 465 mg.

It will be understood that the foregoing description of the invention and the examples set forth are merely illustrative of the principles thereof. Accordingly, the appended claims are to be construed as defining the invention within the full spirit and scope thereof.

We claim:

1. A compound having the formula:

wherein:

the lower alkyl groups have a maximum of six carbon atoms; and

R designates a member of the group consisting of:

hydrogen, lower alkyl having a maximum of six carbon atoms, carbamyl, hydroxy alkyl having a maximum of four carbon atoms and a max-

- imum of two hydroxy groups; carbamyloxy alkyl having a maximum of four carbon atoms and a maximum of two carbamyloxy groups, phenyl benzyl and phenethyl.
2. Hydroxymethyl 2,4,5-trimethylpyrrol-3-yl ketone. 5
3. Methoxymethyl 2,4,5-trimethylpyrrol-3-yl ketone.
4. Carbamyloxymethyl 2,4,5-trimethylpyrrol-3-yl ketone.
5. Ethoxymethyl 2,4-dimethyl-5-propylpyrrol-3-yl ketone.

UNITED STATES PATENT OFFICE
CERTIFICATE OF CORRECTION

Patent No. 3,391,157

July 2, 1968

Irwin J. Pachter et al.

It is hereby certified that error appears in the above numbered patent requiring correction and that the said Letters Patent should read as corrected below.

Column 1, line 15, "havinge" should read -- having --; lines 21 to 28, the formula should appear as shown below:

Column 3, line 33, "proxymethyl" should read -- propoxymethyl --.
Column 4, line 8, "and" should read -- Acid --.

Signed and sealed this 16th day of September 1969.
